ANTENNA

Allen S. Dunbar, Watertown, Mass., assignor, by
mesne assignments, to the United States of
America as represented by the Secretary of War

Application March 26, 1946, Serial No. 657,142

1 Claim. (Cl. 250—33)

1

This invention relates to antennas for high frequency communication systems and more particularly to a beacon antenna suitable for use in high speed aircraft and projectiles.

The installation of radio or radar controlled beacon systems in high speed aircraft and in certain projectiles, such as are known as robot bombs, present a need for a beacon antenna having the following characteristics; small size for minimum drag, unit gain, a substantially uniform azimuth radiation pattern sufficiently broad in elevation to permit maneuvering of the aircraft or projectile, and broad band characteristics. Beacon antennas heretofore proposed although having certain of the desired characteristics have been found to be much too bulky for use on aircraft, projectiles or other similar vehicles designed for high speed. It has been found that a vertically polarized sleeve radiating antenna according to this invention possesses all of the desired characteristics particularly having the advantage of small size with consequent small drag or wind resistance.

Accordingly, it is an object of the present invention to provide an antenna having the above-mentioned characteristics.

It is another object of the invention to provide a beacon antenna suitable for use on high speed aircraft, radar controlled projectiles or similar vehicles and which is characterized by being of simple construction and having very small extension beyond the skin line of the vehicle thereof.

For a better understanding of the invention together with other and further objects thereof, reference is had to the following description, taken in connection with the accompanying drawing:

The single figure is partly a side elevation view and partly a broken away longitudinal sectional view of the antenna according to a preferred embodiment of the invention.

In the drawing, 10 designates the surface or skin of an aircraft, projectile or other similar vehicle of the antenna herein described. Extending from or projecting through and beyond the surface 10 is the antenna 11 according to the present invention. Antenna 11 generally comprises a coaxial conductor having a center conductor 12 and an outer concentric conductor 13. The inner ends of conductors 12 and 13 are adapted to be connected or coupled or may be an extension of an inclosed transmission line such as a coaxial conductor line which feeds energy from a source (not shown) within the vehicle to antenna 11. The outer end 14 of outer conductor

2

13 extends as a circular sleeve projection for a short distance x beyond the skin or surface 10. The inner or central conductor 12 has its outer end portion 15 extending outwardly beyond the end of sleeve 14 with the end thereof being spaced a distance y beyond the skin 10.

The distance x is not more than one-eighth of the wavelength

$$\left(\frac{\lambda}{8}\right)$$

of the radiated energy and is usually considerably less preferably being one twenty-fifth of the wavelength

$$\left(\frac{\lambda}{25}\right)$$

to provide better impedance matching and performance. Distance y representing the effective length of the projecting end portion 15 of the inner conductor 12, which portion may be termed a radiator, is preferably about one-fourth wavelength

$$\left(\frac{\lambda}{4}\right)$$

although it may be somewhat less than a quarter wavelength when the radiator 15 is made relatively thick in cross-sectional dimensions for broad banding purposes.

As a support for inner conductor 12 including radiating portion 15, a washer or bead 16 of a suitable dielectric material may be inserted between inner conductor 12 and sleeve 14 or as shown may be seated against the end of sleeve 14, bead 16 having a bore 17 through which inner conductor 12 is snugly received. A hollow cap 18 of a suitable dielectric material is preferably fitted over the radiating portion 15 to protect the antenna 11 from the effect of variations in weather and/or pressure. The annular base 19 of cap 18 may be secured to the surface 10 in any suitable manner. Preferably, however, a flat circular base plate 20 which may serve as a reflecting surface is secured to the surface 10 and a circular or annular flange member 21 is secured to plate 20, the flange 22 of member 21 being adapted to overlap the annular base portion 19 of cap 18. For ease of production and assembly outer conductor 13, sleeve portion 14, plate 20 and member 21 may be cast or otherwise formed as an integral piece. The inner surface of cap 18 is preferably provided with a shoulder 23 adapted to seat against bead 16 for maintaining the bead 16 and inner conductor 12 in position.

The cross-sectional shape of the radiating portion 15 and of the cap 18 may be either circular as shown or it may be elliptical or streamlined in shape, the elliptical or streamlined shape preferably being utilized when the antenna 11 is used on very high speed vehicles to provide minimum drag. For example, the radiating portion 15 may be an ellipse in cross-section with the major and minor axes having a ratio of the order of six to one. The radiation patterns produced by the antenna 11 having circular, elliptical or streamlined radiators and caps have been found practically identical and uniform in azimuth, assuming the antenna axis to be disposed in a vertical manner, although the non-circular radiators are slightly less broad band than the circular radiators.

Certain aircraft and vehicles offer difficult installation problems in that external attachments such as auxiliary fuel tanks or bombs or parts of the aircraft such as engine nacelles, horizontal or vertical stabilizers, etc., tend to obstruct the view of the antenna in azimuth especially at small angles of roll or pitch. Consequently, such external attachments must be taken into consideration when mounting the antenna. To overcome the possible advantages, the antenna instead of being mounted on the skin or surface of the vehicle itself may be mounted on an airfoil or other suitable projection from the skin surface of the aircraft proper. For example, such an airfoil may be suspended slightly below the aircraft thus permitting a certain amount of roll and pitch without obstructing the antenna and producing by proper shaping of the airfoil a pattern in the transverse plane which is broad enough to permit the aircraft to roll or bank through an angle of 20° or more.

It has been found that an antenna constructed as described herein has all of the desired characteristics from considerations of aerodynamics and electrical performance which have not heretofore been achieved by any antenna heretofore known or proposed.

While there has been described what is at

present considered the preferred embodiment of the invention, it will be obvious to those skilled in the art that various changes and modifications may be made therein without departing from the invention.

What is claimed is:

A beacon antenna for use in high frequency communication systems, particularly on high speed vehicles comprising an electrically conductive base plate adapted to be mounted on the surface of the vehicle and provided with an aperture, a co-axial transmission line mounted through said aperture, said line having an outer conductor secured to said base plate and projecting beyond said plate for a distance of substantially one twenty-fifth of a wavelength at the operating frequency, said line having an inner conductor mounted coaxially in said outer conductor and projecting beyond said base plate for a distance of substantially one quarter of a wavelength, the projecting portions of said inner and outer conductors being adapted to radiate and receive waves of electromagnetic energy, and a hollow cap of dielectric material mounted over the projecting portions of said inner and outer conductors and shaped to conform to the cross-sectional shape of said projecting portions, said cap being spaced from said projection of said inner conductor and having a base portion adjacent said projection of said outer conductor and secured to said base plate.
